SPARK PLUG WITH ANTI-FOULING MEANS
AND FIXED SPARK GAP

Bernard C. Fisher, Jersey City, N.J., assignor to Neutronic Development Corporation, Englewood, N.J.
Filed May 27, 1963, Ser. No. 283,430
1 Claim. (Cl. 313—120)

This invention relates to ignition devices for internal combustion engines and has for a principal object to provide an ignition device which will increase the combustion of the fuel used in the engine and therefore increase the efficiency of the engine.

Another object of the invention is to provide an ignition device for an internal combustion engine which will operate cooler than devices heretofore used and have a much longer life.

Still another object of the invention is to provide an ignition device for an internal combustion engine which will operate clean at all times, remaining free of fouling.

Still another object of the invention is to provide an ignition device for an internal combustion engine which will never need any adjustment of the spark gap, and which will produce a spark at a relatively low voltage.

Other objects of the invention and objects relating to the construction and assembly of the parts of the device will be apparent as the description of the invention proceeds.

The invention is illustrated in the accompanying drawings, in which:

FIGURE 1 is a sectional side view of an ignition device embodying the invention; and

FIGURE 2 is a bottom view of the ignition device of FIGURE 1.

Referring now to the drawings, the ignition device of the invention comprises a tubular shell 1 preferably of steel and having a body portion 2 and a threaded portion 3 which is adapted to be screwed into an engine block; indicated at 4.

The body portion has a larger cross section than the threaded portion, forming a shoulder 5 substantially perpendicular to the axis of the shell.

The shoulder 5 has a groove 6, preferably annular, located so as to permit communication between the space within the groove and the helical path formed between the threads on the shell and those on the engine block 4 when the device is screwed into place on the engine block. The device is used without a gasket, the shoulder 5 being forced tightly against the surface of the engine block. When the groove is annular, the resilience of the steel shell outside of the groove acts to lock the device in place.

At least one aperture 7 is provided in the outer wall of the shell communicating with the groove 6. The arrangement is similar to that disclosed in my U.S. Patent No. 3,016,411, issued January 9, 1962, and provides an air passage from the atmosphere, through the aperture 7, the groove 6, and around the helical path between the threads to the region where the spark is formed at the end of the shell, as will be later described.

The body portion 2 of the shell has a bore 8 which extends about half way to the threaded portion 3 and a bore 9 which terminates at the beginning of the threaded portion 3, these two bores being connected by a tapered shoulder 10. The threaded portion 3 has a bore 11, smaller in diameter than the bore 9 and connected therewith by a tapered shoulder 12.

An insulator 13 is positioned within the shell 1. This insulator comprises an enlarged portion 14 having a diameter such as to fit easily within the bore 8 of the shell and a portion 15 of sufficiently smaller diameter to fit easily within the bore 9 of the shell and a tapered shoul-

der 16 between the portions 14 and 15 which has a taper corresponding to that of shoulder 10.

The insulator is further provided with three portions 17, 18, and 19, of successively decreasing diameters from that of the portion 15, between the portion 15 and the end of the insulator. These portions are separated by shoulders with sharp edges, the shoulders being substantially perpendicular to the axis of the insulator. A tapered shoulder 20 is provided between the portions 15 and 17 having the same taper as the shoulder 12 on the shell.

The insulator has an elongated portion 21 of smaller diameter than the portion 14 which extends from the portion 14 out of the shell and is provided with a tapered shoulder 22 where it joins the portion 14.

The insulator is mounted within the shell so as to provide gas-tight connection between the shell and the insulator. To this end a steel gasket 23 is provided between the tapered shoulder 20 of the insulator and the shoulder 12 of the shell. The space between the body portion of the shell and the insulator is filled with a suitable spark-plug cement 24, and a steel gasket 25 is seated on the tapered shoulder 22. Then the rim 26 of the shell is spun over the gasket 25 to hold the insulator securely in place.

A conductor 27 extends from end to end through a straight, central bore 28 in the insulator. This conductor is made of three parts. An outer rod 29 is positioned within the portion 21 and has a threaded end 30 which extends out of the insulator and is adapted to receive the terminal nut 31. The inner end of the rod 29 is sharpened, as at 32, for making contact with the end of a second rod 32a within the portions 14 and 15.

The other end of the rod 32a terminates in a pin 33 of reduced diameter which extends about half way into the portion 18 of the insulator and into a split nickel tube 34 which is set in the end of the insulator, the end of the tube being flush with the end of the insulator.

I prefer to assemble the conductor by first coating the split tube 34 with Sauerisen spark-plug cement and pressing it into the end of the insulator, with the end of the tube flush with the end of the insulator. Then I wash the excess cement away and allow the remaining cement to set and dry. Then the rod 32a is coated with the cement and inserted in the other end of the insulator followed by the rod 29, the latter being pressed into position so that it pushes the rod 32a and forces the pin 33 into the split tube with which it has a press fit. When the cement dries, the rods are glass-sealed in the insulator with good electrical contact between the two rods and the tube.

The split tube 34 forms a cup-shaped sparking electrode for the device. The inner wall 11 of the shell is provided with inwardly extending projections 35 at the end thereof which are spaced from the insulator a distance of between .030 and .040 inch. These projections form the other electrode. The end of the shell extends beyond the end of the insulator and is bevelled inwardly providing a sloping surface 36 which includes the outer surfaces of the projections 35. The outer edges of these projections are thus flush with the end of the insulator.

Thus constructed, the device provides highly efficient operation of the engine. The sharp edges of the shoulders on the portions 17, 18, and 19 of the insulator act to burn off any deposit of carbon so as to prevent flash-over from the split tube electrode 34 to the shell over the surface of the insulator. The spark occurs from the end of the electrode 34 to the lower surface of one or more of the inwardly extending projections 35 and adjusts itself in length according to variation in compression caused by variation of speed and load. At the same time, air drawn in at high velocity through the groove 6 and

the passage around the threads during the intake stroke cools the entire device and supplies the region around the electrodes with fresh air which is forced into the space around the insulator and the lower portion of the shell with the incoming fuel mixture to provide a highly combustible mixture which insures easy starting and very smooth idling.

I have found that excellent results are produced when the dimensions of the parts adjacent the sparking electrodes are as follows:

Diameter of bore 11	.....	Inches..	.285 to .290
Length of bore 11 including shoulder 12 and projections 35	.....	Inches..	.432 to .437
Diameter of insulator portion 18	.....	do	.235 to .240
Length of insulator portion 18	.....	do	.120 to .125
Diameter of insulator portion 18	.....	do	.235 to .240
Length of insulator portion 18	.....	do	.120 to .125
Diameter of insulator portion 19	.....	do	.200 to .205
Length of insulator portion 19	.....	do	.150 to .155
Outside diameter of split tube electrode 34	.....	do	.125
Inside diameter of electrode 34	.....	do	.075
Distance between end of projections 35 and insulator	.....	Inches..	.030 to .040
Taper of end of shell and projections 35	.....	30°	

I have found that when the tube 34 is made of nickel and the shell is made of non-oxidizing cold rolled steel, such as that known as "C.R.S. BIII3," the surfaces of the electrodes do not oxidize and no high resistance for the spark is built up at these surfaces. Hence a spark is produced at a voltage much lower than that required for an ordinary spark plug. Tests show that the spark occurs at 4,000 volts, leaving a voltage reserve in the coil at all load requirements. There is thus almost no excess heat generated by high current in the device or the associated ignition circuit, and an infallible spark is produced at any engine speed.

While one embodiment of the invention has been shown and described, various modifications may be made in the arrangement of the parts and in the geometry thereof, and I do not therefore wish to limit my invention to what has been shown and described, except as such limitations occur in the appended claim.

What I desire to claim and secure by Letters Patent is:

An ignition device for an internal combustion engine comprising:

- (a) a tubular shell having a body portion and a threaded portion of smaller cross section than said body portion for attaching said device to an engine block, said shell having a first cylindrical bore through the threaded portion thereof and a second cylindrical bore of larger diameter than said first bore within said body portion and providing a tapered shoulder between the two bores,
- (b) an insulator extending through said shell with one end of said insulator terminating near the end of the threaded portion of said shell and the other end of said insulator extending out of said body portion, said insulator within said second bore of said shell

having a diameter to fit easily within said second bore and the portion of said insulator within said first bore having three portions of successively decreasing diameters providing successively greater distances between the inner wall of said shell and said insulator towards said one end of said insulator, said insulator having a tapered shoulder between the largest of said last-mentioned portions and the portion of said insulator within said second bore, the taper of said shoulder being substantially the same as that of said tapered shoulder in said shell, the portions of successively decreasing diameters having shoulders between them with sharp edges,

- (c) a conductor extending through said insulator,
- (d) a cup-shaped electrode set into said one end of said insulator and in contact with said conductor, with the end of said electrode substantially flush with the end of said insulator,
- (e) means for providing a gas-tight connection between said shell and said insulator,
- (f) a shoulder on the outer surface between said body portion of said shell and said threaded portion, said shoulder lying in a plane perpendicular to the axis of said shell,
- (g) a groove in said shoulder,
- (h) at least one aperture between the outer surface of said body portion and said groove, said groove being located so as to provide a communication between said groove and the helical passage around said threads when said device is secured in place in an engine block, and
- (i) at least one inwardly extending projection from the end of said threaded portion of said shell and terminating approximately .035 inch from the end of said insulator containing said cup-shaped electrode, the edges of said inwardly extending projections which are towards the adjacent end of said shell being flush axially with the end of said insulator, and the approximate spacing of the three portions of successively decreasing diameters of said insulator from said shell being respectively .010, .050, and .080 inch.
